LASTING MACHINE

Bernhardt Jorgensen, Marblehead, Mass., assignor to United Shoe Machinery Corporation, Flemington, N. J., a corporation of New Jersey

Application September 30, 1946, Serial No. 700,266

28 Claims. (Cl. 12—1)

1

This invention relates to lasting machines, and is herein illustrated as embodied in a machine for lasting with adhesive. It is to be understood, however, that features of the invention are not limited to lasting with adhesive or to use in a machine of the exact construction herein disclosed.

It is an object of this invention to provide a novel and improved lasting machine which is of relatively simple and inexpensive construction, yet efficient and dependable in operation. With this end in view, and in accordance with a feature of the invention, the herein illustrated machine is provided with novel and improved means for tensioning the stock to be lasted comprising a member having an endless friction surface for engaging one side of the lasting margin of the stock, and movable in a direction extending heightwise of a shoe presented to the machine, a second member for engaging the opposite side of said lasting margin, and means for periodically effecting relative approaching movement of these members to cause the friction surface to exert a frictional drag on the lasting margin thereby to tension the stock heightwise of the shoe.

More particularly, the first-mentioned member consists of an endless flexible element, e. g., a belt, having a friction surface for engaging the outer side of the lasting margin of the stock, while the second mentioned member comprises a lasting shield, associated with a shoe-bottom rest, having an operating surface for engaging the inner side of the lasting margin and movable, with the endless member, during the tensioning action. For effecting the relative approaching movements of these members, an idler pulley is arranged to bear against the endless member and means are provided for causing this idler pulley periodically to move the endless flexible member toward the lasting shield and into frictional engagement with the lasting margin of the stock.

In order to facilitate the lasting operation, and in accordance with a further feature of the invention, the above-mentioned novel tensioning means are arranged also to effect a feeding of the shoe. Preferably, and as herein illustrated, this is accomplished by providing means for moving the endless flexible element, lasting shield and shoe-bottom rest, together and transversely of the direction in which the stock is being tensioned. At the completion of these tensioning and feeding actions, the idler pulley is operated to permit the endless flexible element to move away from the lasting shield and these members,

5 together with the shoe-bottom rest, are moved reversely, i. e., back fed, to their original positions. This cycle of operations is repeated so that the stock is tensioned in different locations, successively, along the edge of the bottom of the shoe.

10 During the aforementioned back-feeding movement of the endless flexible element, lasting shield and shoe-bottom rest, the shoe is held against retrograde movement by pressing means arranged to lay the lasting margin of the tensioned stock down on and to press it against, the bottom of the shoe. This pressing means is operated in time relation to the tensioning and feeding action, mentioned above, and, in accordance with a further feature of the invention, is adapted to move toward the bottom of the shoe with a component of movement inwardly from the edge of the shoe bottom. Preferably, and as herein illustrated, the pressing means comprises a hammer that is pivotally mounted on the end of a lever which is itself pivoted to an oscillated operating arm. The hammer is yieldingly held in a position such that an operating face thereon is inclined to the bottom of the shoe and the lever, on which the hammer is mounted, is yieldable relatively to the operating arm. The arrangement is such that, as the operating arm is oscillated, the hammer first engages the lasting margin of the stock at the very edge of the shoe bottom, then pivots on the end of the lever and swings down to bear flatly against the lasting margin on the shoe bottom, and finally applies pressure to the lasting margin with a definite component of movement inwardly from the edge of the shoe bottom, as the lever yieldingly pivots on the operating arm. This combined pressing and inwiping action of the hammer assures tightness of the stock by avoiding any tendency of the 15 pressure action alone to loosen it around the edge of the shoe bottom.

20 The above and other features of the invention, including various novel details of construction and combinations of parts, will now be more particularly described with reference to the accompanying drawings and thereafter pointed out in the claims.

25 In the drawings,

30 Fig. 1 is a view in front elevation of a machine embodying the invention;

35 Fig. 2 is a view in side elevation of the machine shown in Fig. 1 and with a portion of the machine frame broken away to show the operating mechanism;

Fig. 3 is a view in side elevation, with certain parts in section, of a portion of the operating mechanism in a position assumed during the operation of the machine;

Fig. 4 is a view in front elevation of the operating mechanism in the position shown in Fig. 3; and

Figs. 5 and 6 are views in side elevation, with certain parts in section, of other portions of the operating mechanisms in two different positions assumed during the operation of the machine.

Referring now to the drawings, the operative elements of the machine include a constantly running belt 10 for tensioning the stock to be lasted, also operable to impart a feeding movement to the shoe, a hammer 12 for laying the lasting margin of the tensioned stock down on, and for pressing it against, the bottom of a shoe, a lasting shield, or abutment, 14, for supporting the lasting margin of the stock as it is engaged by the belt, and an idler pulley 16 for moving the belt periodically into engagement with the stock. During the operation of the machine, the shoe being lasted is supported by the operator and held against upward movement, in response to the tensioning action of the belt, by means of a bottom rest 18 associated with the aforementioned lasting shield 14. The belt 10, idler pulley 16, lasting shield 14 and the shoe-bottom rest are all movable as a unit laterally of the machine to effect a feeding movement of the shoe. The hammer 12, which presses the lasting margin of the tensioned stock against the shoe bottom, is operated in time relation to the action of the tensioning and feeding instrumentalities, just mentioned, and operates to hold the shoe against retrograde movement, while these instrumentalities are moved reversely, or back fed, to their original positions. During this back-feeding movement, the idler pulley is shifted rearwardly of the machine to permit the belt to move away from the stock.

The operating elements are supported on, and operated by mechanism contained within a head construction comprising a pair of vertically extending side plates 20, 22, secured at their lower ends, by bolts 24, 24 to a base member 28. This base member is mounted on the upper end of a column 30 of a suitable height to bring the operating elements of the machine to the proper level for the operator. A treadle 32 is arranged to be supported on the floor by means of a bracket 34 and from this treadle a treadle rod 36 extends upwardly through a bore 38 formed in the base member 28. A compression spring 40, interposed between the upper surface of the base member 28 and a collar 42 on the treadle rod, tends to hold the rod in the position shown in Fig. 2.

The belt 10, which may be formed of rubber, fabric or other suitable material, is of the well-known V-type so as to present a flat friction surface 11 and is mounted on a lower drive pulley 50 and an upper pulley 52, see Figs. 1 and 2. The drive pulley 50 is secured to a shaft 54 which is journaled in bearings 56 and 58, carried by the plates 20 and 22 respectively. This shaft extends beyond the plate 22 and is provided with a power input pulley 60 which is driven, from a motor, or other source of power (not shown), by means of a belt 62. The upper pulley 52 is formed integrally with two face cams 64, 66 and a side cam 68 and this whole assemblage is rotatably mounted on a bushing 70, carried by a shaft 72 that is adjustably secured to the upper ends of

the plates 20 and 22 by means of clamp nuts 74, 74, see Fig. 1.

The idler pulley 16 is supported on an arm 80 which extends downwardly from a bracket 82 that is rotatably mounted on a shaft 84 by means of three spaced and apertured ears 86, 88 and 90, see Fig. 4. Also rotatably mounted on the shaft 84, and positioned between the ears 86 and 88 of the bracket 82, is an upwardly extending arm 92 which carries a cam roll 94 adapted to engage the cam 64, Figs. 2 and 3. The ears 86 and 88 of the bracket 82 extend rearwardly and support a boss 96 having a bore 98 in which is positioned a plunger 100. This plunger is yieldingly urged against the arm 92 by means of a compression spring 102 the strength of which may be varied by means of a threaded plug 104. When the cam 64 is in the position shown in Fig. 2, the idler pulley 16 bears lightly against the inside face of the belt 10 and the spring 102 is substantially relaxed. However, when the cam 64 assumes the position shown in Fig. 3, the idler pulley 16 will be projected outwardly to move the belt toward the lasting shield 14, yieldingly through the action of spring 102, and to the position shown. The lower end of the arm 92 is formed with a surface 106 against which a stop screw 108, in the bracket 82, bears when the parts are in the positions shown in Fig. 2. By adjusting the screw 108 the initial position of the pulley 16 with respect to the belt, Fig. 2, may be varied.

The shaft 84 is journaled at one end in a bushing 110, threaded into the plate 20 and held in place by means of a lock nut 112, Fig. 4. On the other end of this shaft, a sleeve 114, having an enlarged portion providing a shoulder 116, is secured, and this sleeve is journaled in a bore 118 in the plate 22. Also rotatably mounted on the shaft 84, between the ear 90 of the bracket 82 and the sleeve 114, is a lever 120, to the outer end of which the shoe-bottom rest 18 is adjustably secured by means of a screw 122, and an arm 124, which is positioned adjacent to the ear 88, of the bracket 82, and is separated from the ear 90 of this bracket by a bushing 126. A compression spring 128, interposed between the bushing 110 and the ear 86, on the bracket 82, tends to hold the shaft 84, together with the bracket 82 and arms 120 and 124, to the right, Fig. 1, with the shoulder 116 on the sleeve 114 against the plate 22. During the operation of the machine, however, these parts are shifted to the left, toward the hammer 12 and to the position shown in Fig. 4, periodically, by means of the cam 68 which acts through a lever 130. This lever is pivotally mounted on the plate 22 by means of a block 132 and trunnion shaft 134 and has at one end a cam roll 136 for engaging the cam 68. A screw 138 is threaded through the other end of the lever 130 and is arranged to engage the end of the shaft 84. A lock nut 140 is provided for holding the screw 138 in adjusted position.

On the inner end of the lever 120 there is a stud 150 which is embraced by a bifurcated end 152 on a lever 154, Figs. 2 and 3. This lever is pivoted to the plate 22 by means of a stud 156 and is connected to the treadle rod 36. When the treadle 32 is released and the rod 36 elevated by the spring 40, the lever 154 is swung in a clockwise direction to the extent determined by a stop pin 158 on the plate 22. This movement of the lever 154 swings the lever 120, in a counter-clockwise direction and to the position shown in Fig. 2, and moves the shoe-bottom rest 18 and

lasting shield 14 outwardly and upwardly away from the belt 10. When the parts are in this position, the outward movement of the belt 10 by means of the cam 64 and idler pulley 16 is not sufficient to bring the friction surface 11 of the belt 10 into contact with the lasting shield 14. However, when the treadle is depressed, the shoe-bottom rest 18 and lasting shield 14 will be swung downwardly and inwardly toward the belt and will assume the positions shown in Fig. 3 in which the swinging movement of the lever 154 has been arrested by an eccentric stop 159 which is mounted on the plate 22. Now, when the belt 10 is moved outwardly by the pulley 16 its friction surface 11 will contact the lasting shield 14, or the lasting margin of stock interposed between the shield 14 and the belt, e. g., the lasting margin of the cover C of a platform shoe comprising an upper U and platform P assembled on a last L. The shoe-bottom rest 18 which bears against the platform P prevents upward movement of the shoe in response to the frictional drag now imposed on the lasting margin of the cover C by the friction surface 11 of the belt 10, which is moving in the direction indicated by the arrow in Fig. 3. The lasting shield 14, which is pivotally mounted on the end of the arm 124 and guided on the shoe-bottom rest by means of a pin 160 and a slot 162, is, however, free to move upwardly. Thus, each time the belt 10 is moved outwardly by the pulley 16, operated by the cam 64, it presses the lasting margin of the cover against the shield 14 and then tensions it in a vertical direction, the lasting shield moving upwardly with the stock during this tensioning action, see Fig. 3. When the belt 10 is withdrawn, as the cam 64 assumes the position shown in Fig. 2, the frictional drag on the stock ceases and the lasting shield is returned to the position shown in Fig. 2 by the action of a spring-pressed plunger 164, associated with the arm 124 and bearing against a surface 166 on the bracket 82, see Figs. 5 and 6.

While the idler pulley 16 is in the position shown in Fig. 3 and the belt 10 still exerting a frictional drag on the lasting margin of the cover C, the cam 68 operates the lever 130 to shift the shaft 84, bracket 82, together with the idler pulley 16 and the arms 120 and 124, which carry the shoe-bottom rest 18 and the lasting shield 14, respectively, to the left and to the positions shown in Fig. 4, and the shoe is moved along a corresponding distance. At the completion of this feeding movement of the shoe, the belt 10 moves away from the lasting shield and out of engagement with the lasting margin of the cover, cam 64 having now rotated from the position shown in Fig. 3 toward that shown in Fig. 2. The idler pulley 16, together with the belt 10, the lasting shield 14 and the shoe-bottom rest 18 are next moved reversely, i. e., back fed, by the action of the spring 128 that is now permitted by the cam 68 which has rotated away from the position shown in Fig. 4. Thus these parts are returned, i. e., back fed, to the position shown in Fig. 1. This cycle of tensioning and feeding actions is repeated so that successive portions of the lasting margin of the cover C are brought into engagement with, and tensioned by, the friction surface 11 on the constantly running belt 10.

At the completion of each feeding action and just before the frictional engagement of the belt 10 with the lasting margin is terminated, by the rearward movement of the belt as above explained, that portion of the lasting margin of the tensioned stock just beyond the belt, i. e.,

to the left, Fig. 4, is laid down on and pressed firmly against the shoe bottom, i. e., platform P, by the hammer 12. The lasting margin of the cover and/or the bottom face of the platform having been previously treated with adhesive, this action of the hammer 12 will cause the cover to be secured to the platform. Thus, as the operation proceeds, successive portions of the lasting margin of the cover are first tensioned by the belt and then laid down on and secured in lasted position to the platform.

The hammer 12 is pivotally mounted on the outer end of a lever 170, by means of a pin 172 in the arm and an arcuate slot 174 formed in a rib 176 on the hammer, Figs. 2, 5 and 6. A coil spring 178, connected at one end to the arm 170 and at the other end to the hammer, tends to hold the hammer yieldingly in the inclined position shown in Figs. 2 and 5. The lever 170 is pivotally mounted, by means of a stud 180, on an arm 182 which is itself pivotally mounted on a cross shaft 184 that is supported by the plates 20, 22. Also pivotally mounted on the stud 180 is a lug 186. The lever 170 has an end 188 which bears against a plunger 190 that is mounted in a thimble 192, threaded into the arm 182. A compression spring 194, in back of the plunger 190, tends to swing the lever in a clockwise direction about the axis of the stud 180 to the extent permitted by the head of a stop screw 196, threaded into the arm 182. A coil spring 198, stretched between the upper end of the arm 182 and a crossbar 200, carried by the plates 20, 22, holds the arm 182, yieldingly, in the position shown in Fig. 2 and with the head of the stud 180 against a stop pin 202 that extends inwardly from the plate 20.

The hammer is operated by oscillating the arm 182 about the axis of the shaft 184 and this action is effected by the cam 66 in the following manner. A lever 210, having a cam roll 212 mounted on its upper end, is pivotally supported on the plate 20 by means of a stud 214. At the lower end of this lever there is an operating nose 216 which is adapted to engage the end of the lug 186 when this lug is swung upwardly to the position shown in Figs. 5 and 6. A coil spring 218, connected to the nose 216 and to the crossbar 200, tends to hold the cam roll 212 against the cam 66 and the lever 210 in the position shown in Fig. 2. For swinging the lug 186 upwardly to bring its end into alignment with the nose 216 on the lever 210, a lever 220 having a spring finger 222, engaging the lug, is provided. This lever is pivotally mounted on a crossbar 224, carried by the plates 20 and 22, and is provided with a bifurcated end arranged to embrace the treadle rod 36. A collar 226 is secured to the treadle rod 36 in a position to swing the lever 220 in a counterclockwise direction, and to the position shown in Figs. 5 and 6, when the treadle 32 is depressed, thus elevating the lug 186 so that its end is in front of the nose 216. When the treadle 32 is released, however, a coil spring 228, connected to the lever 220 and also to the crossbar 200, returns the lever 220 to the position shown in Fig. 2, determined by a stop pin 230, and permits the lug 186 to swing downwardly away from the nose 216, thus terminating the action of the hammer 12.

The action of the hammer 12 may best be understood by reference to Figs. 2, 5 and 6 of the drawings. In Fig. 2, the treadle 32 is released and the lever 210 now merely oscillates without the nose 216 engaging the lug 186 and the ham-

mer 12 is, accordingly, idle. In Fig. 5 the hammer 12 is shown in a position assumed at the beginning of its action and when the arm 182 has been swung inwardly by the cam 66 and lever 210, the treadle now being depressed to elevate lug 186. The hammer is now engaging the lasting margin of the cover C and is holding it against the edge of the platform P. The end 188 of the lever 170, however, is still being held against the stop screw 196 by the plunger 190 and the spring 194 and the hammer 12 is held in the inclined position shown by the spring 178. Now, as the arm 182 is swung still further toward the shoe, by the cam 66 and the lever 210, the hammer 12 is moved to the position shown in Fig. 6 in which it lays the lasting margin of the cover C down on and presses it against the bottom face of the platform P. As the hammer moves from the position shown in Fig. 5 to that shown in Fig. 6, it first pivots on the end of lever 170 so as to lie flatly on the bottom of the shoe. Then, as arm 182 continues to swing outwardly, the lever 170 turns on the stud 180, against the resistance of spring 194. As the arm 182 thus turns, the hammer moves inwardly from the edge of the shoe while still applying yielding pressure to the lasting margin of the cover C. Thus the hammer has an appreciable component of movement inwardly from the edge of the bottom of the platform P so that, in addition to laying the lasting margin down and pressing it against the platform, the hammer also has a definite in-wiping action. This in-wiping action is very important since it tends to draw the lasting margin inwardly from the edge of the bottom of the platform and thus augments the tensioning action of the belt 10. Also, in the absence of such wiping action, the pressing action of the hammer alone might tend to loosen the cover C around the edge of the platform P.

In operating the machine, the shoe is presented thereto, by the operator, bottom up and with the lasting margin of the stock to be lasted, e. g., the cover C, inside of the lasting shield 12, with the treadle released and the operating elements of the machine in the positions shown in Fig. 2. As the treadle is depressed, the operator holds the bottom of the shoe upwardly against the shoe-bottom rest 18 and then permits the shoe to move inwardly, toward the belt 10, with the shoe-bottom rest and lasting shield. Immediately, the tensioning and feeding actions begin as the idle pulley 16 moves the belt 10 outwardly to cause its friction surface 11 to exert a frictional drag on the stock and the cam 68 operates to shift the belt 10, lasting shield 14 and shoe-bottom rest 18 in a direction to feed the shoe. Depression of the treadle also initiates the action of the hammer 12 which lays the lasting margin of the cover C down on, and presses it against, the bottom of the shoe, i. e., the platform P, with an in-wiping action as described above. The operator merely supports and guides the shoe as the lasting operation proceeds. When the lasting operation, which may be continued around the entire periphery of the shoe bottom, or along only a portion thereof, has been completed the treadle is released and the shoe is removed from the machine.

While the herein illustrated machine is particularly adapted for, and has been described as, performing the so-called cover-lasting operation, it will be understood that it is not limited to such use. On the contrary, it is designed for, and capable of, performing a lasting operation

on conventional shoes wherein the lasting margin of the stock, i. e., the upper, is secured to a shoe-bottom member, i. e., an insole, with adhesive.

Having described the invention, what is claimed as new and desired to be secured by Letters Patent of the United States is:

1. In a lasting machine, a member having a friction surface arranged to engage different portions of the lasting margin of stock to be lasted, successively in different locations along the edge of the bottom of a shoe, and operable, intermittently, to apply a frictional drag on the lasting margin to tension the stock heightwise of the shoe and, while maintaining the frictional drag on the lasting margin, to feed the shoe, and means for laying the lasting margin of the tensioned stock down on, and for pressing it against, the bottom of the shoe.
2. In a lasting machine, a member having a friction surface arranged to engage different portions of the lasting margin of stock to be lasted, successively in different locations along the edge of the bottom of a shoe, and operable, intermittently, to apply a frictional drag on the lasting margin to tension the stock heightwise of the shoe and, while maintaining the frictional drag on the lasting margin, to feed the shoe, and means operating in time relation to said tensioning and feeding means for laying the lasting margin of the tensioned stock down on, and for pressing it against, the bottom of the shoe.
3. In a lasting machine, a member having an endless friction surface for engaging one side of the lasting margin of stock to be lasted and movable in a direction extending heightwise of a shoe presented to the machine, a second member arranged to engage the opposite side of said lasting margin, and means for periodically effecting relative approaching movement of said members to cause the friction surface to exert a frictional drag on the lasting margin, thereby to tension the stock heightwise of the shoe.
4. In a lasting machine, a member having an endless friction surface for engaging one side of the lasting margin of stock to be lasted, means for continuously driving said member so as to move said surface in a direction extending heightwise of a shoe presented to the machine, a second member arranged to engage the opposite side of said lasting margin, and means for periodically effecting relative approaching movement of said members to cause said friction surface to exert a frictional drag on the lasting margin, thereby to tension the stock heightwise of the shoe.
5. In a lasting machine, a member having an endless friction surface for engaging one side of the lasting margin of stock to be lasted and movable in a direction extending heightwise of a shoe presented to the machine, a second member arranged to engage the opposite side of said lasting margin, and means for periodically effecting relative approaching movement of said members to cause said friction surface to exert a frictional drag on the lasting margin, thereby to tension the stock heightwise of the shoe, said second member having an operating surface adapted to move with the stock during said tensioning action.
6. In a lasting machine, a member having an endless friction surface for engaging one side of the lasting margin of stock to be lasted and movable in a direction extending heightwise of a shoe presented to the machine, a second mem-

ber arranged to engage the opposite side of said lasting margin, means for periodically effecting relative approaching movement of said members to cause said friction surface to exert a frictional drag on the lasting margin, thereby to tension the stock heightwise of the shoe, and means for moving said members, together and transversely of the direction in which said stock is being tensioned, thereby to feed the shoe.

7. In a lasting machine, a member having an endless friction surface for engaging one side of the lasting margin of stock to be lasted, means for continuously driving said member so as to move said surface in a direction extending heightwise of a shoe presented to the machine, a second member arranged to engage the opposite side of said lasting margin, means for periodically effecting relative approaching movement of said members to cause said friction surface to exert a frictional drag on the lasting margin, thereby to tension the stock heightwise of the shoe, and means for moving said members, together and transversely of the direction in which said stock is being tensioned, thereby to feed the shoe.

8. In a lasting machine, a member having an endless friction surface for engaging one side of the lasting margin of stock to be lasted and movable in a direction extending heightwise of a shoe presented to the machine, a second member arranged to engage the opposite side of said lasting margin, means for periodically effecting relative approaching movement of said members to cause said friction surface to exert a frictional drag on the lasting margin, thereby to tension the stock heightwise of the shoe, said second member having an operating surface adapted to move with the stock during said tensioning action, and means for moving said members, together and transversely of the direction in which said stock is being tensioned, thereby to feed the shoe.

9. In a lasting machine, an endless flexible member having a friction surface for engaging one side of the lasting margin of stock to be lasted and movable in a direction extending heightwise of a shoe presented to the machine, a second member arranged to engage the opposite side of said lasting margin, and means for periodically effecting relative approaching movement of said members to cause the friction surface to exert a frictional drag on the lasting margin, thereby to tension the stock heightwise of the shoe.

10. In a lasting machine, an endless flexible member having a friction surface for engaging one side of the lasting margin of stock to be lasted, means for continuously driving said member so as to move said surface in a direction extending heightwise of a shoe presented to the machine, a second member arranged to engage the opposite side of said lasting margin, and means for periodically effecting relative approaching movement of said members to cause said friction surface to exert a frictional drag on the lasting margin, thereby to tension the stock heightwise of the shoe.

11. In a lasting machine, an endless flexible member having a friction surface for engaging one side of the lasting margin of stock to be lasted and movable in a direction extending heightwise of a shoe presented to the machine, a second member arranged to engage the opposite side of said lasting margin, and means for periodically effecting relative approaching movement of said members to cause said friction surface to exert a frictional drag on the lasting margin, thereby

to tension the stock heightwise of the shoe, said second member having an operating surface adapted to move with the stock during said tensioning action.

- 5   12. In a lasting machine, an endless flexible
member having a friction surface for engaging
one side of the lasting margin of stock to be lasted
and movable in a direction extending heightwise
of a shoe presented to the machine, a second
10 member arranged to engage the opposite side of
said lasting margin, means for periodically effect-
ing relative approaching movement of said mem-
bers to cause said friction surface to exert a fric-
tional drag on the lasting margin, thereby to ten-
15 sion the stock heightwise of the shoe, and means
for moving said members, together and trans-
versely of the direction in which said stock is
being tensioned, thereby to feed the shoe.

13. In a lasting machine, an endless flexible
20 member having a friction surface for engaging
one side of the lasting margin of stock to be lasted,
means for continuously driving said member so
as to move said surface in a direction extending
25 heightwise of a shoe presented to the machine,
a second member arranged to engage the opposite
side of said lasting margin, means for periodically
effecting relative approaching movement of said
members to cause said friction surface to exert a
30 frictional drag on the lasting margin, thereby to
tension the stock heightwise of the shoe, and
means for moving said members, together and
transversely of the direction in which said stock is
being tensioned, thereby to feed the shoe.

14. In a lasting machine, an endless flexible
35 member having a friction surface for engaging
one side of the lasting margin of stock to be lasted
and movable in a direction extending heightwise
of a shoe presented to the machine, a second
40 member arranged to engage the opposite side of
said lasting margin, means for periodically effect-
ing relative approaching movement of said mem-
bers to cause said friction surface to exert a fric-
tional drag on the lasting margin, thereby to ten-
45 sion the stock heightwise of the shoe, said second
member having an operating surface adapted to
move with the stock during said tensioning action,
and means for moving said members, together
and transversely of the direction in which said
50 stock is being tensioned, thereby to feed the shoe.

15. In a lasting machine, a member having an
endless friction surface for engaging one side of
the lasting margin of stock to be lasted and mov-
able in a direction extending heightwise of a shoe
55 presented to the machine, a second member ar-
ranged to engage the opposite side of said lasting
margin, means for periodically effecting relative
approaching movement of said members to cause
the friction surface to exert a frictional drag on
60 the lasting margin, thereby to tension the stock
heightwise of the shoe, and means for laying the
lasting margin of the tensioned stock down on,
and for pressing it against, the bottom of the
shoe.

16. In a lasting machine, a member having an
65 endless friction surface for engaging one side of
the lasting margin of stock to be lasted, means
for continuously driving said member so as to
move said surface in a direction extending height-
wise of a shoe presented to the machine, a second
70 member arranged to engage the opposite side of
said lasting margin, means for periodically effect-
ing relative approaching movement of said mem-
bers to cause said friction surface to exert a fric-
tional drag on the lasting margin, thereby to ten-
75 sion the stock heightwise of the shoe, and means

for laying the lasting margin of the tensioned stock down on, and for pressing it against, the bottom of the shoe.

17. In a lasting machine, a member having an endless friction surface for engaging one side of the lasting margin of stock to be lasted and movable in a direction extending heightwise of a shoe presented to the machine, a second member arranged to engage the opposite side of said lasting margin, and means for periodically effecting relative approaching movement of said members to cause said friction surface to exert a frictional drag on the lasting margin, thereby to tension the stock heightwise of the shoe, said second member having an operating surface adapted to move with the stock during said tensioning action, and means for laying the lasting margin of the tensioned stock down on, and for pressing it against, the bottom of the shoe.

18. In a lasting machine, a member having an endless friction surface for engaging one side of the lasting margin of stock to be lasted and movable in a direction extending heightwise of a shoe presented to the machine, a second member arranged to engage the opposite side of said lasting margin, means for periodically effecting relative approaching movement of said members to cause said friction surface to exert a frictional drag on the lasting margin, thereby to tension the stock heightwise of the shoe, means for moving said members, together and transversely of the direction in which said stock is being tensioned, thereby to feed the shoe, and means for laying the lasting margin of the tensioned stock down on, and for pressing it against, the bottom of the shoe.

19. In a lasting machine, a member having an endless friction surface for engaging one side of the lasting margin of stock to be lasted, means for continuously driving said member so as to move said surface in a direction extending heightwise of a shoe presented to the machine, a second member arranged to engage the opposite side of said lasting margin, means for periodically effecting relative approaching movement of said members to cause said friction surface to exert a frictional drag on the lasting margin, thereby to tension the stock heightwise of the shoe, means for moving said members, together and transversely of the direction in which said stock is being tensioned, thereby to feed the shoe, and means for laying the lasting margin of the tensioned stock down on, and for pressing it against, the bottom of the shoe.

20. In a lasting machine, a member having an endless friction surface for engaging one side of the lasting margin of stock to be lasted and movable in a direction extending heightwise of a shoe presented to the machine, a second member arranged to engage the opposite side of said lasting margin, means for periodically effecting relative approaching movement of said members to cause said friction surface to exert a frictional drag on the lasting margin, thereby to tension the stock heightwise of the shoe, said second member having an operating surface adapted to move with the stock during said tensioning action, means for moving said members, together and transversely of the direction in which said stock is being tensioned, thereby to feed the shoe, and means for laying the lasting margin of the tensioned stock down on, and for pressing it against, the bottom of the shoe.

21. In a lasting machine, an endless flexible member having a friction surface for engaging

the outer side of the lasting margin of stock to be lasted and movable in a direction extending heightwise of a shoe presented to the machine, and means for periodically moving said flexible member into engagement with the outer face of the lasting margin to cause the frictional surface to exert a frictional drag on the lasting margin, thereby to tension the stock heightwise of the shoe, a member for supporting the shoe against heightwise movement in response to said frictional drag, and means for holding said lasting margin against the frictional surface of the endless member comprising a member, associated with said supporting means, arranged to engage the inner side of the lasting margin and movable, heightwise of the shoe, with said flexible member during the tensioning action.

22. In a lasting machine, an endless flexible member having a friction surface for engaging the outer side of the lasting margin of stock to be lasted and movable in a direction extending heightwise of a shoe presented to the machine, and means for periodically moving said flexible member into engagement with the outer face of the lasting margin to cause the frictional surface to exert a frictional drag on the lasting margin, thereby to tension the stock, a shoe-bottom rest for engaging the bottom of the shoe to hold it against movement in response to the tensioning of the stock, and means for holding said lasting margin against the frictional surface of the endless member comprising a member, associated with said shoe-bottom rest, arranged to engage the inner side of the lasting margin and movable, heightwise of the shoe, with the flexible member during the tensioning action.

23. In a lasting machine, an endless flexible member having a friction surface for engaging the outer side of the lasting margin of stock to be lasted and movable in a direction extending heightwise of a shoe presented to the machine, means for periodically moving said flexible member into engagement with the outer face of the lasting margin to cause the frictional surface to exert a frictional drag on the lasting margin, thereby to tension the stock heightwise of the shoe, a member for supporting the shoe against movement in response to the tensioning of the stock, means for holding said lasting margin against the frictional surface of the endless member comprising a member, associated with said supporting means, arranged to engage the inner side of the lasting margin and movable, heightwise of the shoe, with the flexible member during the tensioning action, and means for moving said aforementioned members, together as a unit, in a direction extending lengthwise of the shoe to feed the shoe.

24. In a lasting machine, an endless flexible member having a friction surface for engaging the outer side of the lasting margin of stock to be lasted and movable in a direction extending heightwise of a shoe presented to the machine, means for periodically moving said flexible member into engagement with the outer face of the lasting margin to cause the frictional surface to exert a frictional drag on the lasting margin, thereby to tension the stock heightwise of the shoe, a shoe-bottom rest for engaging the bottom of the shoe to hold it against movement in response to said tensioning of the stock, means for holding said lasting margin against the frictional surface of the endless member comprising a member, associated with said shoe-bottom rest, arranged to engage the inner side of the lasting margin

and movable, heightwise of the shoe, with the flexible member during the tensioning action, and means for moving said flexible member, shoe-bottom rest and holding means, together in a direction extending lengthwise of the shoe, to feed the shoe.

25. In a lasting machine, the combination with means for tensioning stock to be lasted heightwise of a shoe, said means being also operative, during its tensioning action, to effect a feeding movement of the shoe, of means for laying the lasting margin of the tensioned stock down on and for pressing it against, the shoe bottom comprising a hammer constructed and arranged, first to engage said lasting margin at the edge of the shoe bottom, then to lie flatly against the lasting margin and apply pressure thereto with a component of movement inwardly from the edge of the shoe bottom.

26. In a lasting machine, the combination with means for tensioning stock to be lasted heightwise of the shoe, said means being also operative, during its tensioning action, to effect a feeding movement of the shoe, of means for laying the lasting margin of the tensioned stock down on, and for pressing it against, the shoe bottom comprising a pivotally mounted hammer constructed and arranged, first to engage the lasting margin at the edge of the shoe bottom, then to lie flatly against the lasting margin and apply pressure thereto with a component of movement inwardly from the edge of the shoe bottom.

27. In a lasting machine, the combination with means for tensioning stock to be lasted heightwise of a shoe, said means being also operative, during its tensioning action, to effect a feeding movement of the shoe, of means for laying the lasting margin of the tensioned stock down on,

and for pressing it against, the shoe bottom comprising a hammer pivotally mounted on the end of a lever, and means for oscillating said lever in time relation to the action of said tensioning and feeding means so as to cause said hammer, first to engage said lasting margin at the edge of the shoe bottom, then to lie flatly against the lasting margin and apply pressure thereto with a component of movement inwardly from the edge of the shoe bottom.

28. In a lasting machine, the combination with means for tensioning stock to be lasted heightwise of a shoe, said means being also operative, during its tensioning action, to effect a feeding movement of the shoe, of means for laying the lasting margin of the tensioned stock down on, and for pressing it against, the shoe bottom comprising a hammer pivotally mounted on the end of a lever, an arm for supporting said lever, means for pivotally mounting said lever on the arm yieldingly and means for oscillating said arm in time relation to the action of said tensioning and feeding means to cause the hammer, first to engage the lasting margin at the edge of the shoe bottom, then to lie flatly against the lasting margin and apply pressure thereto with a component of movement inwardly from the edge of the shoe bottom.

BERNHARDT JORGENSEN.
